UNITED STATES PATENT OFFICE,

HERBERT M. FRIENDLY, OF PORTLAND, OREGON.

TELEPHONE SYSTEM.

Application filed May 20, 1921. Serial No. 471,165.

To all whom it may concern:

Be it known that I, HERBERT M. FRIENDLY, a citizen of the United States, residing at Portland, in the county of Multnomah and State of Oregon, have invented a certain new and useful Improvement in Telephone Systems, of which the following is a full, clear, concise, and exact description, reference being had to the accompanying drawings, forming a part of this specification.

The present invention has for its broad objects, the improvement of telephone systems in general and more particularly automatic and semi-automatic telephone systems.

The invention in the specific form chosen for the illustration herein, contemplates a so-called two-wire common battery automatic telephone system as has been widely used, the present invention occasioning certain departures from equipments heretofore known so far as I am aware, in attaining the new objects, while retaining certain operative functions which are known.

The exampled form of the present invention chosen to illustrate it, contemplates its adaptation to a comprehensive automatic telephone exchange system. It has the following and other objects:—

a. To provide means in an automatic selector (first or succeeding) whereby if controlling impulses are applied before the selector has completed its automatic functioning it will be caused to lock and thereby render the circuits non-responsive to succeeding impulses which might cause a misdirected connection to be established. In the event that the selector should be caused to lock as referred to, a specific tone will be applied to the leading-in telephonic conductors, audible to the calling subscriber, indicating that the call has been vitiated, so that a new attempt can be made to effect the connection. The means is also provided to record through a meter device the number of times the selector encounters all the trunks in a certain level or group as busy.

b. To provide means in an automatic connector whereby when it encounters a called line and finds it busy it will, in addition to applying a busy tone to its leading-in conductors audible to the calling subscriber, apply a special tone briefly audible along the line leading to the called subscriber and to the line telephonically related therewith. That is to say, where a telephonic connec-

tion is established between a calling and a called subscriber and a new call to one of the said subscribers is attempted not only will the subscriber directing the new call receive a tone indicating the busy state of the line called, but the two parties in telephonic relation will be apprised that an attempt is being made by a third party to reach one of the lines in the established connection between the subscribers.

c. To provide means in an automatic group-selecting connector whereby if all the lines in a group accessible to the connector has been found busy by the connector, a busy tone will be applied to its leading-in conductors, audible to the calling subscriber, and in addition, a brief, special tone will be applied, audible to all the parties in telephonic relation over the lines of the group. That is to say, should the group-selecting connector test a plurality of outgoing lines (which may be termed trunk lines, possibly extending to a private branch exchange switchboard) and finds all of them busy, a tone will be applied, audible to the subscribers talking on each established connection. The object of this application of tone is to apprise all parties concerned who are holding lines, that a connection to one of the lines of the group is being attempted and that it is unsuccessful, due to all lines of the group being busy.

d. To provide means at a private exchange, for example, wherein if all but one (any one) of a group of trunk lines connected thereto are busy, a special tone will be applied audible to parties telephonically related to these busy lines, indicating the condition. A meter device is provided at the private branch exchange to integrate the number of times this condition has ensued. That is to say, the meter will indicate the total number of times all but one of the group of lines has been busy and, therefore, leaving but one idle line open and available for service.

There are other objects of the present invention which will appear.

Referring further to paragraph "a". In automatic telephone exchange operation where selector switches automatically function following the directed selection of a trunk group and where, thereafter, a number of busy trunks are encountered and passed over in seeking a disengaged trunk,

the period of automatic selecting functioning is, in instances, prolonged beyond the period that the calling subscriber waits before initiating the transmission of the succeeding series of impulses constituting the next following digit of the number being called. It will thus appear that under this condition the calling subscriber (or a mechanical calling means functioning automatically from a set-up condition) will have started a series of impulses before the selector has found and seized a leading-out trunk extending to a succeeding switch. Under this condition the call will be vitiated. In instances wherein the premature digit series sent involves a plurality of impulses, the selector will have had time to have found and seized an idle leading-out trunk before all of the impulses constituting the digit being sent by the calling subscriber will have transpired, and therefore one or more impulses of the series intended to operate a switch on the remote end of the properly seized line will be effective to the hunting selector. It will, under the last assumed condition, be manifest that a less number of impulses than intended will reach the selector on the remote end of the seized trunk. This will mean that a wrong trunk group, as indicated by a smaller number of directive impulses received, will be step-by-step selected by the said remote selector and an idle trunk thereof connected with. A call from this point on, in the direction of a called subscriber may proceed normally responsive to the impulses transmitted from a calling device in control of the calling subscriber, but it, of course, will be manifest that a wrong called subscriber will be reached. Conditions such as this are annoying to both parties of the established connection and tend to create a distrust in automatic switching means, and perhaps prompt service complaints to be made entailing costs to the operating company in making investigations, the seat of trouble of which cannot be definitely placed. The function of the selector of the present invention will definitely forestall the possibility of establishing a wrong connection where such conditions are that of the calling subscriber dialing a succeeding digit series too quickly has ensued, and moreover, will apprise the calling subscriber that it will be fruitless to go ahead with the call until he has replaced his receiver and has re-initiated the call. It will appear that subscribers will soon accustom themselves to the fact that too rapid dialing will not always be effective, and will therefore, adjust the calling to the practical considerations of the equipment.

The second feature under paragraph "a." of metering the number of times selectors of a group encounter all trunks of a

certain level or group busy, has its convenience in exchange systems by enabling an automatic observation to be made to ascertain if ample trunking facilities have been provided to certain divisions of the exchange. The selectors of a group can be adjusted at will to record the number of times a busy condition has been found in any particular trunk group or level, and therefore absolute records are made, regardless of the number of times selectors of a group may find a busy condition in other accessible trunk groups not concerned with the particular observation being conducted.

Referring further to paragraph "b": In automatic exchange systems, wherein there is no operator to inform the parties to a telephonic conference that a third subscriber is calling for one of the connected lines, a telephonic conversation acts to bar the subscribers' premises against all callers regardless of the relative importance of the call under way to the call which is sought to be established by a third calling party. A function involved in the present invention, therefore, affords an element of convenience and security to users in that they will know immediately that there is someone seeking connection with one of the lines involved in the telephonic conference so the conversation ensuing may be terminated as promptly as is expedient to enable the party attempting the connection to re-initiate the call presently with a reasonable certainty of successfully completing it. It will thus appear that this function will serve not only a convenience to all subscribers concerned, but that it will forestall complaints being lodged to seek the assistance of the operating company in getting the subscribers hold of a prolonged conversation, perhaps, to release their connected lines.

Referring further to paragraph "c": In automatic telephone exchange operation wherein groups of trunk lines (or other lines) extend from a main branch exchange of an operating company to the premises of a subscriber, it has been found that the number of trunk lines subscribed for are often fewer than the traffic requirements warrant. Under these conditions calling subscribers more or less often find themselves barred by reason of all trunks testing busy because of the trunk being connected to a line, or by reason of the calling, following the initiation of a call on the trunk not having been completed simply. This entails a delay to calling parties and occupies exchange equipment time. So, with this in view, the present invention comprehends means to apply a brief tone audible to all parties holding telephonic connection over any one of the trunk lines, consequent upon a call being made, and all of the trunks being found busy. The practical result is that upon those

holding the trunks hearing the tone they will be prompted of the condition and terminate the conversations as quickly as possible so as to relieve the condition, or it will prompt the subscriber that he has not provided for, or subscribed for enough trunk lines to take care of the traffic demands between the exchange system and his establishment.

Referring further to paragraph "b": Subscribers using a plurality of trunk lines, for example, as contemplated in the foregoing paragraph "c", wish to avoid the condition wherein the calling subscriber will find his establishment barred by reason of finding all trunks busy. The subscriber is interested in having his employes make as brief use of the lines as possible in conversation, and further, wants lines constantly available for outgoing traffic from his establishment. It will be manifest that the present invention operates towards forestalling the said undesirable condition from ensuing, by reason of the fact that when all but one of the trunk lines are busy, regardless of any demand, a tone will be briefly applied, audible along each and every one of the connections over the engaged trunks which will apprise those using them, or any one holding one simply, of the condition and, therefore, prompt the release of the trunk as soon as possible. From the operating company's viewpoint, this functioning forestalls busy trunk conditions being encountered with the attendant delays, annoyances and undesirable conditions enumerated. To the subscriber it will influence his employes to the briefest consistent use of the trunk lines and conduce to maintaining an open way to and from his establishment at all times, and it will also serve to keep him posted as to whether he has provided for or subscribed for a sufficient number of trunks to take care of his traffic requirements.

The present invention, in view of the foregoing general statements and the specific descriptions to follow, has wide adaptations, and moreover would in many instances involve a different application for the same nominal use in an exchange. It will also appear that other uses more or less equivalent to those enumerated may be made of the present invention without departing from its scope, in view of the subjoined claims.

In accordance with this invention as applied to the system chosen for its elucidation, each line terminates in a lineswitch (also termed a pre-selector hereinafter), and the latter have common access to a plurality of first selectors. The first selectors have common access to a plurality of groups of connectors, which latter groups have common access to certain groups of subscribers' lines. Other connector groups have access to certain groups of subscriber's lines.

In the accompanying drawings:—

Fig. 1 shows a subscriber's automatic telephone T leading to a pre-selector PS, and the latter, in common with other pre-selectors not shown, are in selective relation to a selector A of the present invention.

Fig. 2 shows a connector B of the present invention, together with an accessible subscriber's line leading to a telephone T². The telephone T² is similar to telephone T.

Fig. 3 shows a calling telephone T³ which is similar to telephone T. The telephone T³ leads to a pre-selector PS³ which is similar to pre-selector PS. The pre-selector PS³, in common with other pre-selectors not shown, have common access to first selector FS³ which is similar to selector A. First selector FS³, in common with other first selectors not shown, have common access to connector CON³. Connector CON³ has common access with connector B, and other connectors not shown, with telephone T². Telephone T² has its leading-out lines terminating in a pre-selector similar to PS, indicated simply by the cut-off relay CO, it not being thought necessary to show all the pre-selectors in detail in the present descriptions.

Fig. 4 shows a group-selecting connector C, well known in the art, having access to a group of trunks disposed in the manner contemplated in the present invention. Also, a pre-selector PS⁴ connected with one of the trunks of the group. It is similar to PS.

Fig. 5 shows certain novel equipments at the private branch exchange ends of the trunks, shown as leading out from the bank contact group shown in Fig. 4. Telephone T⁵ thereof is similar to T.

Fig. 6 shows a schematic detail of the arrangement of bank and co-operating wipers shown in H of Fig. 5.

Fig. 7 shows the arrangement of the various indicated figures in one organization of the equipments in the present invention, which will be detailed hereinafter.

Fig. 8 shows an arrangement of the various indicated figures in a second organization of equipments in the present invention, which will be detailed hereinafter.

Fig. 9 shows a cord-pair for use with the springjacks shown in Fig. 5.

Referring to certain of the various figures:—

In Fig. 1, T is the usual series type of automatic telephone having a calling device 121 of the general class as shown in British patent to Dicker, No. 29,654 of 1910. The pre-selector PS is of the general class as shown in U. S. patent to Lamb, No. 1,193,160 granted August 1, 1916. The first selector A is of the general class shown in U. S. patent to Keith & Erickson, No. 815,321 granted March 13, 1906, of course, modified in mechanical and circuit details to op-

erate on the well known so-called two-wire principle and in accordance with the present invention.

In Fig. 2, B is a connector of the general class as shown in U. S. patent to Keith & Erickson, No. 815,176 granted March 13, 1906, of course, modified in mechanical and circuit details to operate on the well known so-called two-wire principle and in accordance with the present invention.

In Fig. 4, C is of the general class as is connector B in Fig. 2, and is known in the art as a group-selecting connector. The novelty relating to it as regards the present invention is in the bank connections and equipments associated therewith. Pre-selector PS⁴ (similar to PS) is well known in the art.

In Fig. 5, the element H is an automatically functioning member incorporating a motor-magnet M, and which provides for a continuous normal rotary movement, each step of which is resultant to the de-actuation of motor-magnet M, the mechanical details of which may be assumed as similar to that shown in the said cited patent to Lamb, or the pre-selector PS⁴, bearing in mind that it is preferred, though not necessary, for the stepping or advancement of the wipers of element H to be responsive to the de-actuation of motor-magnet M rather than directly upon its actuation.

To simplify the drawings and descriptions, battery and ground are shown as independent sources throughout, wherever applied, but it is to be understood that the system is of the common battery type. In the descriptions, when a circuit is traced to a winding, the opposite terminal of which is shown applied to grounded battery or to ground, the described circuit is to be considered as traced to ground through the winding to battery, or direct to ground as indicated.

The performance of the equipments will be detailed under different assumed operative conditions, bearing in mind that the equipment elements may be variously organized in the assembly of a system.

Referring to the accompanying drawings:—

Assume a call from telephone T to telephone T², the telephone number of which is "211". The figures will be assembled as shown in Fig. 7. Upon the calling subscriber at telephone T initiating the call by removing the receiver from the switchhook of telephone T the pre-selector PS will function in the well known manner and extend the connection to the first selector A, which latter is assumed to be the first seizable first selector of a group accessible to the pre-selector PS. A circuit exists after the seizure of A from grounded battery, upper winding of relay 101, armature 102, conductor 103, wiper 104, of pre-selector PS, conductor 105, telephone T, conductor 106, wiper 107, conductor 108, armature 109, lower winding of relay 101, "eleventh-rotary" cam-spring 110 to grounded spring 112, relay 101 actuating. An operative circuit can now be traced from the winding of slow-releasing relay 114 to grounded armature 115. Also, grounded contact 116 will apply ground to conductor 117 and through wiper 118 to the winding of cut-off relay 119, thus maintaining the pre-selector, and guarding the line leading to telephone T against intrusion, all in the well known manner.

Upon the calling subscriber operating the calling device 121 in accordance with the first digit "2" of the called number, the energizing circuit of relay 101 heretofore traced will be opened two times and relay 101 will therefore, de-actuate and re-actuate two times resultant thereto. Upon each retraction of armature 115 an operative circuit can be traced from said armature, armature 122, armature 123, winding of slow-releasing relay 124, upper armature of the right-hand relay to the winding of the vertical magnet 125. The slow-releasing relay 124 will actuate consequent upon the first current impulse being established, and it is sustained over the lapse between the impulses and for its period after the final impulse. The vertical magnet will operate two times and raise the shaft carrying wipers 127, 128 and 129 two vertical steps into alignment with the second level of bank contacts. At the time relay 124 first attracted its armature 131, bearing in mind the operation of vertical magnet 125 set forth, a circuit is established from grounded battery through winding of shunted relay 132, off-normal spring 133, armature 131, conductor 117 to grounded contact 116, relay 132 actuating.

At the expiration of the period of relay 124, whereupon its armature 131 retracts, a circuit can be traced from the winding of the rotary magnet 134, armature 135, armature 131, conductor 117 to grounded contact 116, the rotary magnet actuating and advancing the wipers 127, 128 and 129 one rotary position into engagement with the first set of bank contacts 136, 137 and 138 respectively. Incident to the first rotary movement rotary off-normal springs RON will engage, however to no operative purpose at this juncture, but to prepare a circuit the purpose of which will appear presently.

It will be assumed that the first set of bank contacts are those of a busy trunk and, therefore, that bank contact 136 will constitute ground potential. Then, upon the retraction of the rotary magnet armature 139, a circuit is established from grounded battery through the winding of relay 132, spring 133, armature 139, conductor 140, armature 141, conductor 142, wiper 127 to

bank contact 136. Remembering that bank contact 136 constitutes ground potential, relay 132 will re-actuate and establish the before described energizing circuit for the 5 rotary magnet 134, causing it to actuate and advance wipers 127, 128 and 129 a further rotary step into engagement with the successive set of bank contacts in co-operative relation thereto. Should the second bank 10 contact engaged by wiper 127 also constitute ground potential the same operative function will transpire as described and cause the wipers to be advanced a second rotary step, this cycle of operations continuing until a bank contact not constituting ground potential is engaged by wiper 136.

It will now be assumed that this non-grounded contact finally engaged by wiper 127 is the first contact 136 of the level. 20 The operation of the selector upon encountering said 136 as ungrounded, about to be described will be the same as had it encountered one or more grounded contacts 25 and then encountered a non-grounded one. Upon wiper 127 engaging ungrounded contact 136 there will be no energizing circuit reestablished for relay 132. The resistance and adjustment of relay 132 is such that 30 it will not actuate when its winding is included in series relation with the winding of relay 143. Bearing in mind the non-grounded condition of wiper 127, a circuit can now be traced from grounded battery, 35 winding of relay 132, spring 133, armature 139, conductor 140, winding of relay 143, spring 144, conductor 117 to grounded contact 116, relay 143 actuating and relay 132 remaining un-actuated. A circuit can now 40 be traced from grounded contact 116, conductor 117, armature 141, conductor 142, wiper 127 to bank contact 136, applying ground potential to the said 136, thereby 45 guarding its trunk against intrusion by other selectors accessible to it through multiplied bank contact sets. The foregoing general operation of selector A is well known in general principle, but it will appear there are other features introduced into 50 this selector.

It will now be assumed that while the selector wipers 127, 128 and 129 are being rotated, seeking an idle trunk, that the calling subscriber operates the calling device 121 in accordance with the second digit "1". 55 Bearing in mind that relay 143 is in normal position during the said rotation, it will be manifest that relay 101 will be caused to de-actuate and re-actuate one time. 60 Upon its de-actuation a circuit will be established from grounded armature 115, armature 122, rotary off-normal springs, RON to the winding of relay 145, causing it to actuate. A locking circuit will be established for the said 145 through its

armature 146, conductor 117, to grounded contact 116. A closed path will be established consequent to the operation of relay 145 from grounded armature 147 to conductor 142, thus applying a false busy condition effective as if wiper 127 is encountering grounded bank contacts and it will, therefore, continue to rotate until its carrying shaft is blocked by encountering the eleventh-rotary cam-spring CS. Under this condition ground potential is maintained on both winding terminals of relay 143 so it is inoperative to its armatures, and relay 101 and its dependent relay 114 will continue to remain in control of the calling 70 subscriber at telephone T. A circuit can now be traced from grounded special tone source 150, armature 151, conductor 152, spring 110, lower winding of relay 101, armature 109, through the described path 75 including telephone T, armature 102, upper winding of relay 101 to battery. The tone will thus be audible to the calling subscriber at T and it will indicate to him the ensuing condition. It will be manifest that 80 the wipers 127, 128 and 129 having rotated off the last operative set of bank contacts, of which there would usually be ten, and would, therefore, have no operative relation 85 with a successive switch which might be affected by manipulations of the calling device 121 were it inadvertently continued by reason of the calling subscriber not listening 90 for the tone. However, no operative effect will have occurred by reason of the 95 transmitting of impulses after relay 145 acts. 100

Upon the calling subscriber replacing the receiver, opening the described energizing circuit to relay 101, it is caused to de-actuate 105 followed by its dependent relay 114 and the restoration of the pre-selector PS in sequence. An operative circuit can now be traced from grounded armature 115, armature 122, armature 123, off-normal spring 110 115 to the winding of release magnet 155 causing it to actuate and restore the selector A.

Assume that the set of springs SCS are 115 adjusted to be engaged by a cam on the shaft when it attains the eleventh-rotary position when the shaft is functioning with the wipers in registry with the third bank level, for example, the selector having been operated accordingly. This condition would 120 ensue if the trunks leading from this level were all found busy. It is to be understood in this connection that the cam designed to operate the said springs SCS will be adjustable at will so that the selector can be readily set to cause this cam to function upon the eleventh-rotary position being attained at any level. Of course, all selectors in a group would be similarly adjusted with regard to the cam-springs corresponding to

SCS on the various selectors respectively. Under the conditions of the cam-spring SCS operating, a circuit will be closed from grounded tone source 156, winding of meter drive-magnet 157, common conductor 158, spring 159, conductor 160, armature 151, conductor 152, spring 110 (bearing in mind that eleventh-rotary cam-springs CS are operated under all eleventh-rotary conditions 10 regardless of levels), lower winding of relay 101 over the described path including telephone T, upper winding of relay 101, to grounded battery, causing the said 157 to operate and step the meter drum 161 the angular distance representing one unit. The tone emanating from source 156 will manifestly be audible to the calling subscriber. The meter magnet 157 and its co-operating drum 161 are of a well known form of 20 electro-magnetic meter device, in which a plurality of drums are in correlation, each drum representing a numerical order, progressively. The meter electro-magnetic core is slow-releasing to prevent it from de-actuating and re-actuating by a short lapse of current, such as might be introduced by calling device 121, and thereby registering falsely.

Conductor 158 is a common conductor 30 leading to the meter magnet 157, which is also common. The said 158 is common to a group of selectors having access to the same group of trunks on the third level, so that one meter serves a plurality of selectors. It 35 will be manifest, therefore, that the number of times the selectors of a group have rotated off the operative bank contacts into the eleventh-rotary position on the third level will be indicated on the meter drums.

Should the wiper 127 rotate off the last 40 operative bank contact co-operative thereto in normal operation on a level not effective to the spring set SCS, the set of springs CS would be the only set operated. Under this condition a circuit can be traced from grounded tone source 156, cam spring 163, 45 spring 159, conductor 160, armature 151, conductor 152, spring 110, lower winding of relay 101 over the traced path including the telephone T and the upper winding of relay 50 101 to grounded battery, the tone from tone source 156 being audible to the calling subscriber at T, and the ground through the said tone source 156 replaces the ground on spring 112 disengaged when spring 110 is 55 engaged so that relay 101 is maintained until the subscriber at telephone T replaces the receiver.

The operation of Fig. 1 being now clear, 60 the description will be continued from the instant that relay 143 actuated consequent to wiper 127 encountering ungrounded bank contact 136. A circuit can now be traced from grounded battery through the upper 65 winding of relay 201, spring 202, conductor

203, bank contact 137, wiper 128, conductor 166, armature 102 over the described path including telephone T to armature 109, conductor 167, wiper 129, bank contact 138, conductor 204, spring 205, lower winding of 70 relay 201 to ground, relay 201 actuating. An operative circuit can now be traced from the winding of slow-releasing relay 207 to grounded armature 208. Ground from armature 209 is applied to conductor 210 75 and to bank contact 136 before the period of relay 114 has expired following the actuation of relay 143 and, therefore, no lapse of ground occurs to conductor 142, so that relay 143 and relay 119 will be maintained 80 from connector B.

Upon the calling subscriber at telephone T operating the calling device 121 in accordance with the second digit "1", relay 201 will be caused to de-actuate and re-actuate 85 one time, responsive thereto. A circuit will be established upon the re-traction of armature 208 from it through armature 212, armature 213, series winding of slow-releasing relay 214, winding of vertical magnet 215, 90 sideswitch wiper 216 in first position to grounded battery. Relay 214 will attract its grounded armature 217 and the vertical magnet 215 will step its shaft carrying wipers 220, 221 and 222 one vertical step, 95 aligning with the first level of bank contacts. Upon the attraction of armature 217 a circuit is closed therefrom to the winding of private magnet 223, causing it to actuate and incidentally attract its armature 224 against its co-operating grounded contact 225. The mechanical details relating to the private magnet 223 are well known in the art so that it is sufficient to say here that upon the expiration of the period of relay 214 following the re-attraction of relay 201 the private magnet 223 will de-actuate and permit the sideswitch wiper 216 and its companion wiper 218 to advance into their second position.

Upon the calling subscriber at telephone T operating the calling device 121 in accordance with the third digit "1", relay 201 will de-actuate and re-actuate one time in accordance therewith as before, this time, however, grounded armature 208 applies its ground through armature 212, armature 213, winding of relay 214, armature 226, winding of rotary magnet 227, sideswitch wiper 216 in second position to grounded battery. Armature 217 will energize the private magnet 223 in a manner as before set forth, and the rotary magnet 227 will be caused to operate one time and advance the wipers 220, 221 and 222 one rotary position into engagement with bank contact 230, 231 and 232 respectively. Upon the retraction of armature 217 its period after the attraction of armature 208, the private magnet 223 will be de-energized to permit the sideswitch 120 125

wiper 216 and its companion wiper 218 to advance into their third position, however, this advancing of wipers 216 and 217 will depend upon whether wiper 220 finds 5 ground potential on bank contact 230, as will appear presently.

Assuming that bank contact 230 does not constitute ground potential, upon the private magnet de-energizing and the said wipers 10 216 and 218 advancing to their third position, a circuit can be traced from ground, wiper 218, winding of relay 235, wiper 216 to grounded battery, relay 235 actuating. Also, from ground, wiper 218, wiper 220 to 15 bank contact 230, serving to energize the pre-selector cut-off relay and guard the line leading to telephone T^2 against intrusion through other connectors accessible to it, as connector CON^3 , for example. A circuit 20 can now be traced from grounded interrupted ringing current source 236, armature 237, armature 238, wiper 222, bank contact 232, line conductor 239, condenser 240, signal device 241 at telephone T^2 , line conductor 242, bank contact 231, wiper 221, armature 243, armature 245, inside winding of relay 246 to grounded battery. The relay 246 is 25 so designed that it will be inoperative to the signaling current emanating from source 236 and traversing the signal device 241, due to 30 a condenser 240 being included therewith, but is operative to direct currents such as would traverse the said inside winding of relay 246 were it energized over a conductive path rather than the inductive path involved in condenser 240.

Upon the called subscriber at telephone T^2 removing the receiver and closing the conductive path therethrough, the winding of 40 relay 246 will operatively energize it so that its armatures will be attracted. A circuit can now be traced from grounded off-normal spring 248, armature 249, through the lower winding of relay 250, conductor 251, armature 237, armature 238, wiper 222, bank contact 232, line conductor 239, received at telephone T^2 , line conductor 242, bank contact 231, wiper 221, armature 243, armature 245, conductor 252, upper winding of relay 250 45 to grounded battery, relay 250 actuating. A locking circuit to maintain armatures of relay 246 attracted will be completed from grounded battery, through outside winding of relay 246, armature 249, to grounded 50 spring 248, insuring that the armatures of relay 246 will remain attracted until off-normal spring 248 is freed, the off-normal springs being operated on the first off-normal movement of the shaft. It is manifest 55 that the attraction of armatures 253 and 254 will serve to transpose the relation of the leading-in line conductors with respect to the windings of relay 201, and, therefore, the current traversing the calling subscriber's telephone receiver at telephone T will be 60

reversed in direction. This reversal has no operative function in the present invention, and moreover, is old in the art as generally applied to connectors.

The telephonic circuit is now established 70 from the calling subscriber at telephone T in the direction of the called subscriber over the traced circuit to conductors 203 and 204 and through condenser 256 to conductor 252 and over the traced circuit including the 75 receiver of called telephone T^2 , conductor 251, condenser 257 to conductor 204, transmission current being supplied to the calling telephone T from the winding of relay 201 and to the called telephone T^2 from the 80 windings of relay 250. The disposition of the said relays 201 and 250 is not new in connectors, as generally applied. The restoration of connector B occurs upon the last 85 party to the conversation replacing his receiver, as is well known in this general type of connector, and for that reason will not be detailed.

The present invention as it is applied in connector B involves the following: The 90 special grounded tone source 260, armature 261 and its co-operating contact 262 on release magnet 263, conductor 264, leading from said armature 261, armature 265 on relay 207, conductor 266 leading from the resting contact co-operating with armature 265 to armature 267 on the busy relay 268, conductor 269 leading from the working contact of said armature 267 to telephonic conductor 270 leading to wiper 222. It will thus appear that upon the attraction of armature 267 the special tone will be applied from ground to one limb of the telephonic conductor leading to wiper 222. The functioning of selector B with 95 particular reference to the present invention will be taken up more fully presently.

It will be assumed that a calling subscriber at telephone T^3 initiates a call by removing the receiver from the switchhook 301, whereupon pre-selector PS^3 will automatically function in the manner well known and attain connection with the first available first selector FS^3 in the manner well known. Assume further that the calling subscriber at telephone T^3 is calling subscriber at telephone T^2 the telephone number of which, as was stated hereinbefore, is "211", accessible to connector B and connector CON^3 and other connectors. It, of course, is manifest that the telephone T is in a different group to the telephone T^3 and, therefore, the respective pre-selectors of the lines leading to the said telephones T and T^3 are in access to different groups of first selectors, selector A being in one group and selector FS^3 being in another group.

Telephone T^3 now being in control of selector FS^3 , upon the calling subscriber at telephone T^3 operating the calling device 302

in accordance with the first digit "2" of the desired telephone line, the wipers of first selector FS³ will be caused to be raised to align with the second level of bank contacts thereof and then be automatically rotated-in until a first idle trunk is encountered, when it will seize in the manner as fully set forth in the descriptions relative to selector A. Wipers 305, 306 and 307 are, therefore, in seized engagement with bank contacts being assumed as the first set in the second level of the first selector FS³. Upon the calling subscriber at telephone T³ calling the last two digits "1—1" of the desired telephone line the wipers 315, 316 and 317 will be caused to be raised one vertical step into alignment with the first bank level of the connector and then directedly rotated-in into engagement and seizure of the first set 10 of bank contacts 318, 319 and 320 respectively, the connector CON² projecting ring-ing current and otherwise functioning as fully set forth in the description relative to connector B in effecting connection to telephone T², and the cut-off relay 271 will be energized due to the sideswitch wiper 321 being in its third position, in the manner well known and as detailed with respect to connector B. The subscriber at telephone 20 T² will respond as before.

Under the condition ensuing, that of a telephonic circuit existing between calling telephone T³ and called telephone T², the telephone T, pre-selector PS, selector A and connector B are in their normal positions and bank contact 230 constitutes ground potential and thus serves to guard the telephonic circuit established between telephone T³ and telephone T² against intrusion by connector B or other connectors that may have access normally to the line leading to telephone T².

It will now be assumed that the calling subscriber at telephone T has established a telephonic connection in the direction of telephone T² as has been heretofore fully described and that when wiper 220 engages bank contact 230, it now encounters the busy ground potential assumed due to the established connection between telephone T³ and telephone T². Bearing in mind the described functioning of connector B up until the wiper 220 engaged bank contact 230 wherein sideswitch wipers 216 and 218 were in their second position, it will be manifest that the ground potential now found on bank contact 230 will at this instant be applied over wiper 220, sideswitch wiper 218 in second position, conductor 272, spring 273, winding of relay 268, spring 274, winding of private magnet 223 to grounded battery, thus maintaining the private magnet 223 energized after the retraction of armature 217 the period of relay 214 after the impulse to the rotary magnet 227 was im-

parted by way of advancing wiper 220 into engagement with bank contact 230. Bearing in mind that as long as the private magnet 223 remains energized the sideswitch wipers 216 and 218 are not permitted to advance into their third position, it will appear that the described energizing circuit for relay 235 will not be established and, therefore, it will not attract its armatures 243 and 238 by way of completing the telephonic circuit from the calling telephone T to the wipers 221 and 222 which are in electrical engagement with bank contacts 231 and 232 respectively.

At the time the winding of relay 268 became energized it attracted its armatures and established a locking circuit from grounded battery, winding of the private magnet 223, spring 274, winding of relay 268, armature 275, to grounded spring 248, thus maintaining private magnet 223 and the relay 268 locked actuated. This circuit will not be opened until the shaft of the connector restores to normal.

Under the locked condition last described, a circuit can be traced from grounded busy tone source 276, armature 277, telephonic conductor 251, condenser 257, conductor 204 over the described path, including calling telephone T, to conductor 203, condenser 256, upper winding of relay 250 to grounded battery, the tone being audible to the calling subscriber at telephone T and indicates to him that the connector B has encountered a busy line, that is, the line leading to telephone T is busy. In view of the locked condition of the private magnet and relay 268, no selective operation of connector B can follow. However, the calling subscriber at telephone T can replace his receiver and open the hereinbefore described energizing circuit for relay 201 causing it to de-actuate followed by its dependent relay 207 in sequence. Bearing in mind that relay 250 has not yet actuated, a circuit can now be traced from grounded armature 209, off-normal spring 278, armature 279 to the winding of the release magnet 263, causing it to actuate and restore the shaft of connector B, carrying the wipers 220, 221 and 222 to normal.

The armature 265 of relay 207 is adjusted to make its co-operating resting contact upon retraction before the armature 209 makes its co-operating resting contact upon retraction. Also, the release magnet 263, which carries an electrical armature 261, and a co-operating resting contact 262, is given electrical and mechanical properties which produce a retarded effect upon the armature 261. That is to say, the armature 261 will not disengage its resting contact 262, which may follow the armature over a portion of its movement, until after an appreciable interval elapses after the energi-

zation of the said release magnet 263. The object of this characteristic will appear. It is not new to retard the operation of magnets for an appreciable period after the energization by the so-called slugging of the electro-magnet, or by introducing dashpot devices that require a prolonged torque to overcome.

In light of the foregoing it will appear 10 that for an appreciable time following the establishment of the described circuit from grounded armature 209 to grounded battery through the winding of the release magnet 263, a circuit can be traced from 15 grounded special tone source 260, resting contact 262, armature 261, conductor 264, armature 265, conductor 266, armature 267, conductor 269, conductor 270, wiper 222, bank contact 232 to conductor 239. From 20 conductor 239, which in view of the established connection between telephone T³ and telephone T², is common to the two said telephones, and bearing in mind the relationship of the front and back bridge relays in 25 connectors CON^a, it will be manifest that the tone traced to conductor 239 will traverse the receivers of the said telephone T³ and T² and reach ground in connector CON^a through the lower winding of the 30 back bridge relay and through the telephonic condenser corresponding to 257 in connector B and upper winding of the front bridge relay corresponding to 201 in connector B to grounded battery. The said 35 tone applied audible to the calling subscriber at telephone T³ and the called subscriber at telephone T² will endure until armature 261 attracts from its resting contact 262. It will thus be clear that upon 40 the calling party at telephone T replacing his receiver to restore the connection following his receiving a busy signal when attempting to complete a call, a tone indicating the condition is applied for an interval 45 audible to the subscriber on the line called and also audible to the subscriber on the line in telephonic relation with it through the exchange apparatus. This apprises them 50 that some one is attempting to reach one of their lines so that they may terminate the service and render the lines seizable as soon as expedient.

In the foregoing description, with particular reference to the special tone source 260, 55 a special characteristic in the release magnet 263 was set forth, the object of which was to retard the attraction of armature 261 from its resting contact 262. It is preferred to provide an extra armature 280 and its co- 60 operating resting contact 281 on relay 201 to enable conductor 264 to be removed from armature 265 and attached to said armature 280, and to enable conductor 266 to be removed from the contact upon 65 which armature 265 rests and attach it

to resting contact 281. This change would be made by the attendant if for any traffic or other reasons it were desired to prolong the prompting tone (as we may term the tone applied to an established 70 connection as has been set forth), for a period equal to the period of relay 207. That is to say, that the prompting tone applied to conductor 270 will now traverse the path from grounded tone source 260, resting 75 contact 262, armature 261, conductor 264, armature 280, resting contact 281, conductor 266, armature 267, conductor 269, to said conductor 270. It will be manifest that this circuit will be established for the period 80 or relay 207 before it de-actuates and energizes the release magnet 263, so that the prompting tone will have a duration of application to conductor 270 correspondingly 85 longer than described where the prompting tone path included armature 265 in lieu of armature 280 and its resting contact 281. It will be apparent under the latter arrangement that should the calling subscriber at 90 telephone T operate his calling device 121 and thereby cause relay 201 to operate responsive thereto (however to no operative purpose dependent upon the vertical magnet 215 or the rotary magnet 227 due to the sideswitch wiper 216 being in the second position and armature 226 on relay 268 being attracted), the established prompting tone circuit traced through armature 280 and resting contact 281 will become established 95 upon each de-actuation of relay 201, and, therefore, a series of prompting tone applications will be made to conductor 270, audible through the telephones T³ and T² corresponding to the digit called by the calling subscriber at 100 telephone T. Of course, if no manipulation of the dial 121 is made and the calling subscriber at telephone T simply replaces the receiver, the one prolonged prompting tone application will be made as described. 105 While applying a series of prompting tones may be desirable and preferred in order to convey an urgency, it is a matter open to divergent opinions on the part of traffic and operating telephone men, and also general 110 subscribers, as to which may be preferred, and moreover, it may be desirable to change the method of operation in this detail from 115 time to time.

It is also preferred to provide an extra set 120 of normally disengaged off-normal springs 286 and 287 to enable conductor 264 to be disconnected from armature 261 and applied to spring 286 and to disconnect the conductor leading to resting contact 262 and apply it to 125 spring 287. This change would be made by the attendant if for any traffic or other reason it were desired to prolong the application of the prompting tone to conductor 270 from the time armature 265 retracts until 130

- the connector B has its shaft restored to normal, and not have the tone disconnected from conductor 270 upon the attraction of armature 261 which is an appreciable time 5 before the shaft has started to restore. Of course, where the springs 286 and 287 are operative and used the armature 261 and its co-operating resting contact 262 have no operative purpose.
- 10 Under the condition wherein springs 286 and 287 are operatively employed, upon the retraction of armature 265 (or 280, depending upon which armature is operatively used) the special tone will be applied from 15 source 260, spring 287, spring 286, conductor 264, armature 265, (or 280) conductor 266, armature 267, conductor 269 to telephonic conductor 270. In view of the fact that relay 268 will remain locked until spring 248 20 disengages from its co-operating spring consequent upon the shaft restoring to normal, the prompting tone will be applied until the shaft restores to normal. However, it is to be borne in mind that the prompting tone 25 will not be audible along conductor 239 after the wiper 222 disengages from bank contact 232 consequent to the operation of the release magnet 263 in effecting the restoration, and moreover, the tone standing on wiper 30 222 while restoring will be momentarily applied to co-operating bank contacts corresponding to bank contact 232 which may be passed over in releasing, in case the wiper has been rotated in past the first contact.
- 35 The duration of this latter falsely applied prompting tone will be so brief as to not ordinarily be discernable.
- Referring now to Fig. 8 for the assembly of figures in the organization of equipments 40 illustrating other features of the present invention as applied in the exemplified telephone system illustrative of it. It will now be assumed that the calling subscriber at telephone T desires to effect a telephonic 45 connection to telephone T', located in a private exchange on the premises of a subscriber. It will also be assumed that there are four trunk lines accessible to a group-selecting connector C (of well known type 50 as has been stated at the outset) on its first bank level, and, therefore, calling the same nominal telephone number will insure that the first accessible trunk of the group of four will be automatically selected and 55 seized. Terminating each one of the said four trunks at the private exchange end is a springjack 501 and also a calling signal device, as will appear presently. Terminating each one of the local lines, as for example the line leading to the said telephone T', is a springjack 502 and a pre-selector PS'. The operation on the part of the calling subscriber at telephone T' is therefore 60 to establish a primary connection to the springjack 501 as shall be detailed presently,

gain the response of the operator at the private branch exchange through the said 501, and then be connected by the operator through the agency of a connecting or switching cord-pair, as shown in Fig. 9, 75 from the springjack 501 to springjack 502. The operator will signal the called subscriber at telephone T' and the connection will progress until it is taken down by the operator as will be detailed more fully presented.

The telephone number of the group of trunks shown leading from its corresponding group of bank contacts at the right of connector C is "411". Therefore, in effecting the connection to this latter telephone number the calling subscriber at telephone T will initiate the call and gain the seizure of selector A in the manner as hereinbefore detailed. The calling device 121 will then be manipulated in accordance with the first digit "4" of the called number, whereupon, the selector A will function in the manner as hereinbefore detailed, however, this time the wipers thereof 127, 128 and 129 rotating-in and hunting and seizing a first disengaged trunk on the fourth bank level, which will be assumed to be the trunk leading from the first set of bank contacts 175, 176 and 177 leading over conductors 178, 179 and 180 respectively to connector C.

A circuit can now be traced from grounded battery upper winding of relay 401, spring 402, conductor 179, bank contact 176, wiper 128 over the hereinbefore described path including the telephone T, wiper 129, bank contact 177, conductor 180, spring 403, lower winding of relay 401 to ground, relay 401 actuating. An operative circuit can now be traced from the winding of slow-releasing relay 405 to grounded armature 406. Upon the calling subscriber at telephone T manipulating the calling device 121 in accordance with the second digit "1" of the telephone number of the called trunk group the wipers 407, 408, 409 and 410 will be caused to be raised one vertical step into alignment with the first level of bank contacts shown in the drawing. Upon the calling subscriber at telephone T manipulating the calling device 121 in accordance with the third (and final) digit "1" of the telephone number of the called trunk group, the said wipers 407 to 410 (inclusive) will be caused to be controllably stepped one rotary position into engagement with the first set of bank contacts 412 to 415 respectively. The connector C being well known in the art, will not require detailed description here. Suffice it to say, however, that should the wiper 408 have encountered ground on bank contact 413 it would have automatically rotated or advanced a step, the said wipers 407 to 410 then engaging the bank contacts 416 to 419, and should the wiper

408 again find ground potential, this time on bank contact 417, the said wipers 407 to 410 would be caused to be automatically rotated or advanced a step to the next rotary position. This automatic functioning will continue until the wiper 408 engages a bank contact that does not constitute ground potential, or until the wiper 407 engages a bank contact constituting ground potential.

In this connection it may be stated that it is well known in the art to have the bank contacts engageable by wiper 407 of all but the last trunk of a group free of operative attachments and, therefore, not subject to constituting ground potential, however, to have the last bank contact of a group engageable by wiper 407 tied to the last bank contact of the group engageable by wiper 408. And, therefore, if the last bank contact of the group which is engageable by the wiper 408 should constitute ground potential the last bank contact of the group engageable by wiper 407 will constitute ground potential. It is well known that if wiper 407 encounters ground potential the automatic rotation of the connector C will be stopped thereby, and a tone indicative that the entire group of trunks (of which there may be one only or more), are busy. From this it follows that the last pair of contacts of each group have the companion contacts engageable by companion wipers 407 and 408 electrically tied. In practice a single level may constitute a group or it may be single lines extending therefrom. In the latter case, the bank contacts thereof engageable by companion wipers 407 and 408 will be electrically tied so that in the event that the bank contact engageable by wiper 408 constitutes ground potential by reason of its being busy, the companion bank contact engageable by wiper 407 will also constitute ground potential, causing the connector testing to be set in its busy-testing condition upon its wiper 407 resting on the grounded bank contact at the instant of test, and, therefore, will not rotate into an irrelevant group.

By reference to Fig. 4, it will be noted that the last companion contacts 421 and 422 of the group of four trunks engageable by companion wipers 407 and 408 are tied together electrically, the circuit including the winding of slow-releasing relay 425. Heretofore, so far as I am aware, the tying of these contacts has been direct and have not included an electro-magnetic energizing circuit of an operative device such as relay 425. However, the resistance of the winding of said relay 425 does not offer enough obstruction to operatively affect the normal functioning of connector C, should some of the groups of trunks accessible to said connector C have the last companion contacts

adapted to be engaged by wipers 407 and 408 directly connected by means of a tie-wire and, therefore, not including an obstruction such as is involved by relay 425. It will be manifest, in view of the last statement, that the functions gained through the employment of the present invention need not, therefore, be introduced into all the trunk groups accessible to a connector.

The operation of the connector C upon its wiper 408 encountering group potential on bank contacts 413, 417, 426 and 422 will function as follows, bearing in mind that because of bank contact 422 constituting ground potential bank contact 421 will also constitute ground potential. Bearing in mind also, that sideswitch wipers 427 and 428 are in their second position during the time wipers 407 to 410 are rotating in the operation of hunting for an idle trunk of a group. When wiper 407 encounters ground potential on bank contact 421 (being the last trunk position of the group) this ground potential will be conducted over conductor 430, spring 431, armature 432, winding of relay 433, sideswitch wiper 427 to grounded battery, relay 433 actuating. A locking circuit for relay 433 can now be traced from off-normal grounded spring 437, conductor 438, armature 439, spring 431, armature 432, winding of relay 433, sideswitch wiper 427 to grounded battery. The armature 444 being attracted, the rotary magnet 445 is incapacitated. During the time relay 433 is energized a circuit can be traced from tone source 446, conductor 447, armature 448, telephonic conductor 449, condenser 450, conductor 180 over the described path including telephone T, conductor 179, condenser 451, upper winding of relay 452 to grounded battery, the said tone being audible to the calling subscriber at telephone T, and indicates to him that all of the trunks of the group comprised in telephone number "411" are busy and that no further functioning of connector C can take place until after it is restored to normal by his replacing the receiver as set forth.

The ground potential found by wiper 407 on bank contact 421 ensued, perhaps, by reason of some other accessible connector having its wiper corresponding to 408 in seized relation to the bank contact co-operative thereto corresponding to bank contact 422 and which is in multiple relation to 422, it being understood that in practice there would ordinarily be a plurality of connectors similar to C in a group in access to groups of multiple bank contacts in corresponding relation to the said connectors so that a call can be completed to a trunk group in a similar manner regardless of what connector is functioning.

In this connection it may be stated when a connector rotates on to a set of bank

contacts of an idle trunk, which in this instance will be assumed the fourth or last trunk of the group, wiper 407 and also wiper 408 not finding ground potential or either bank contact 421 or 422, the private magnet 455 will be de-energized, permitting the sideswitch wipers 427 and 428 to move into their third position, whereupon conductor 456 leading to wiper 408 will constitute ground potential (received through sideswitch wiper 428) and applies it to bank contact 422 and its multiples, and of course, to the companion contacts, as 421, thereto. It is now manifest that the ground potential derived through wiper 407 and conductor 430 which caused relay 433 to actuate was derived through the winding of relay 425 (which is common to one group), causing it to attract its armatures. Also, due to the attraction of armature 439 on relay 433 the traced circuit, including conductor 430, was opened forthwith after the said operative establishment of a circuit including it, consequently deenergizing relay 425. However, due to the slow-releasing characteristic of relay 425, it will remain actuated for a period after its de-energization. During the time relay 425 has its armatures attracted, grounded tone source 460 is applied through the said latter armatures over conductors 461, 462, 463 and 464 to bank contacts 415, 419, 465 and 466 respectively. It is manifest that the said bank contacts 415, 419, 465 and 466 are in electrical continuity with the lower limb of the trunks one to four respectively, and bearing in mind that since they are in a busy condition either by being in seized relation with a connector similar to C, or is in a seized relation through a pre-selector as PS⁴. The conductors 467, 468 and 469 of PS⁴ lead to a first selector A in which the said latter conductors correspond to conductors 117, 103 and 108 respectively. It will be clear that the said grounded tone source 460 will project a tone which will traverse the said lower telephonic limbs, and telephones operatively connected between said lower limbs and the upper companion limbs leading to bank contacts 414, 418, 470 and 471 of trunks one to four inclusive, and find a path to ground through a winding of either or both of relays corresponding to 452 and 401 of connector C, a winding of a relay corresponding to 101 of selector A of first selector similar to A (if the selector has not seized), the winding of a relay corresponding to relay 201, of a connector similar to B, or through the winding of a battery supply relay such as 960 in a cord-pair similar to Fig. 9; all depending upon whether each trunk concerned is busy due to the fact an outgoing call to the private branch exchange through a connector as C has been made, or whether the busy con-

dition is due to a call having been initiated at the private branch exchange as will be detailed presently and, therefore, involves a pre-selector as PS⁴, and possibly a cooperating first selector as A and a connector 70 successive to the said selector.

It is to be remembered in this connection that it is contemplated that each trunk of the four in a group shown as leading to the right margin in Fig. 4 is equipped 75 for two-way service, as is the first trunk, and that, therefore, each trunk has a pre-selector connected thereto similar to PS⁴. The first trunk only of the group is shown connected to a pre-selector, being pre-selector PS⁴, in order not to unduly complicate the drawings. The group of first selectors companion to A accessible to the pre-selectors PS⁴ and PS has likewise been omitted 80 from the drawings to avoid unduly complicating the drawings. But in view of the statement that conductors 467, 468 and 469 of pre-selector PS⁴ correspond to conductors 117, 103 and 108, which latter conductors are accessible to wipers 118, 104 and 107 respectively, it is not thought necessary 85 to detail these selectors companion to A in order to convey a comprehensive understanding of the system contemplated under the present invention, and, moreover, it is 90 old in the art to complete connections from a pre-selector through successive switches in the direction of a called subscriber in a telephone system.

It is now manifest, in view of the foregoing, that if a connector encounters a called trunk group in which all the trunks thereof are busy, either by reason of the service thereon being initiated from a calling telephone in the main exchange, or by reason 10 of the service thereon being initiated from the private branch exchange, not only will the calling subscriber in the main exchange attempting to effect a connection to the private branch exchange receive the customary busy tone as heretofore known in the art, but the function contemplated under the present invention will be brought into requisition wherein a brief special tone will be applied over the telephonic conductors of all the busy trunks of the group, audible to subscribers in telephonic relation thereto, regardless of which end of the trunk is the initiating end. This tone will indicate to all auditors that a call has been attempted directed towards one of the group of trunks leading between the private branch exchange and the main exchange and that it has not been completed due to finding 11 all the trunks busy.

Referring now to Fig. 5 wherein four individual sets or pairs of trunk terminating equipment units are indicated. To avoid unduly involving the drawings, the first trunk of the group of four heretofore re- 12 13

ferred to as leading from bank contact sets accessible to connectors as C, is the only one shown in schematic detail though enough has been shown of the corresponding equipment of the succeeding three trunks in the group to clearly show the details of operation and construction.

In order to impart a complete understanding of the operation at the private branch exchange, a call will be assumed as completed over the first trunk of the group, that is, that wiper 408 does not encounter ground potential when it engages bank contact 413 (bank contact 412 being clear of attachments and having no operative object under any condition). As is well known, sideswitch wipers 427 and 428 are in the second position when the wipers 407 to 410 are advanced into engagement with bank contacts 412 to 415 respectively, and due to armature 475 being attracted incident to the wipers being driven the first step, the inside winding of private magnet 455 will be energized and, therefore, restraining the sideswitch wipers 427 and 428 from moving into their third position. However, upon the retraction of armature 475, the private magnet 455 will de-energize, and therefore is will permit the wipers 427 and 428 to advance into their third position. This would not have occurred had wiper 408 encountered ground potential on bank contact 413, and communicated it over conductor 456, wiper 428, through the outside winding of private magnet 455 to grounded battery. Inasmuch as wipers 427 and 428 have now advanced into their third position, a circuit can be traced from grounded sideswitch wiper 428, conductor 456, wiper 408 to bank contact 413, thus applying ground potential to said 413 and its multiples. The circuit from conductor 456 can be traced through the winding of relay 476, wiper 427 to grounded battery, relay 476 actuating. A circuit can now be traced from interrupted ringing current source 477, armature 478, armature 479, spring 480, wiper 409, bank contact 414, conductor 481, armature 503 to tip spring 504 of springjack 501 and through the upper winding of slow-releasing relay 505 to ground. The relay 505 is designed to be operative to the said source of ringing current 477.

Relay 505 will attract its grounded armatures 506 and 507. Calling lamp 508 will glow, indicative that a call has been completed over the first trunk of the group and that a calling subscriber is awaiting the response of the attendant at the private branch exchange. A circuit can now be traced from grounded armature 506 to the sleeve thimble 509 of springjack 501 and through armature 510 to the winding of relay 512, relay 512 actuating. A circuit can now be traced from grounded contact

513 to private bank contact 514 and bank contact f of element H; also, winding of relay 515 will be disconnected from bank contact 514 and other connections in multiple relation thereto by reason of the attraction of armature 516. It will be noted in this connection that a non-operative circuit path can be traced from the grounded battery through lower winding of relay 505 ring spring 517 of springjack 501, armature 518, conductor 519, bank contact 415, wiper 410, armature 482, armature 483, through the inside winding of relay 484 to grounded battery. The polarity of the grounded battery sources at the opposite ends of the traced path are of the same and have the same voltage and, therefore, will exert no effect upon relay 505.

It will be assumed now that upon the attendant at the private branch exchange observing the glowing of lamp 508, the said attendant will insert switching plug 902 into springjack 501, whereupon the windings of relay 505 will become disconnected from the traced paths. A circuit can now be traced from ground through the winding of relay 903, sleeve 904 of plug 902, sleeve thimble 509 of springjack 501, armature 510 to the winding of relay 512, the windings of relays 903 and 512 being in series relation. Relay 512 will be maintained actuated and relay 903 will actuate. A circuit can now be traced from interrupted ringing current source 477 over the described path to spring 504, thence to tip 905 of plug 902, spring 906 of dialing key 907, spring 908 through the winding of the polarized relay 909, spring 910, spring 912, ring 913 of plug 902, spring 517 of springjack 501, armature 518, conductor 519, bank contact 415, wiper 410, armature 482, armature 483, inside winding of relay 484 to grounded battery. Relay 484 has the same characteristics as were defined in relation to relay 246 of connector B and, therefore, it will actuate.

The direction of the winding on polarized relay 909 is such that with current traversing it derived as traced through the inside winding of relay 484 it will not move its armature 914 from the normal position shown in the drawing, but should the current be reversed in direction it will operate its armature 914 to disengage its resting contact 915. A circuit can now be traced from grounded armature 916, armature 914, resting contact 915, clearing lamp 917 to grounded battery, the said lamp 917 glowing. It is to be borne in mind that the described circuit, including the winding of polarized relay 909, endures very briefly, only until relay 484 actuates, whereupon the circuit traced from armature 478 to armature 483, and including the winding of polarized relay 909, is now continued from

armature 478 over conductor 485, upper winding of relay 452 to grounded battery, and from armature 483, conductor 449, lower winding of relay 452, conductor 487, armature 488, conductor 438 to grounded off-normal spring 437, relay 452 actuating. The direction of current traversing the winding of polarized relay 909 being thus reversed from that first described, its armature 914 is caused to be attracted from its resting contact 915, lamp 917 extinguishing. It will be noted in this connection that a locking circuit is established for relay 484 from its outside winding conductor 487, armature 488, conductor 438, to grounded off-normal spring 437, and that this locking circuit will be maintained until the connector has been released to normal in a manner well understood, and generally as has been set forth 20 in connection with connector B.

The telephonic circuit now exists from calling telephone T over the traced path to conductors 179 and 180 and from conductor 179, condenser 451, conductor 485, armature 478, armature 479, spring 480, wiper 409, bank contact 414, conductor 481, armature 503, spring 504 of springjack 501, tip 905 of plug 902, spring 906, spring 908, condenser 920, conductor 921, spring 922 of key 923, spring 924 to tip 925 of plug 926, and from conductor 180, condenser 450, conductor 449, armature 483, armature 482, wiper 410, bank contact 415, conductor 519, armature 518, ring spring 517 of springjack 501, ring 913 of plug 902, spring 912, spring 910, condenser 927, conductor 928, spring 929, spring 930 to ring 931 of plug 926. Listening key 935 will be manipulated, completing a circuit from telephonic conductor 921 through the operator's receiver 936 secondary winding of induction coil 937 to telephonic conductor 928, the calling subscriber at telephone T and the private branch exchange attendant being thus in telephonic communication.

It will be assumed that the calling subscriber at telephone T requests the connection extended to telephone T^e. The private exchange attendant will now insert switching plug 926 into springjack 502. A circuit can now be traced from ground through winding of relay 945, sleeve 946, of plug 926 to sleeve thimble 521, conductor 522, winding of relay 523 in pre-selector PS^e, armature 524 of motor magnet M^e to grounded battery. The mechanical adjustment between the armatures of relay 523 and relay 525 of pre-selector PS^e is well known, so it will be understood that armature 526 operates to disassociate the winding of relay 525, and that armature 527 operates to disassociate grounded contact 528, but that no other operative effect is produced by armature 526, or by the lower armatures of said relay 523. Relay 945 is now operated due to the

establishment of the traced circuit including its winding, so that a circuit can now be traced from grounded armature 950, armature 951, clearing lamp 952 to grounded battery, lamp 952 glowing. The attendant will now briefly depress self-restoring key 923 whereupon ringing current from source 953 will be applied from spring 954, spring 924, tip 925 of plug 926, spring 527' of springjack 502, line conductor 528' through condenser 529, signal bell 530, line conductor 531, spring 532 of springjack 502, sleeve 931 of plug 926, spring 930, spring 955 to the opposite pole of the ringing source 953, signal bell 530 operating to summons the called subscriber at called telephone T^e. Upon the called subscriber at telephone T^e responding by removing the receiver from the switchhook, a conductive circuit for direct current will be established between conductors 528' and 531 including the receiver, calling device 533, and transmitter 534 so that the telephonic circuit previously traced to tip 925 and ring 931 of plug 926 is now extended to and includes telephone T^e. A circuit can also be traced from grounded battery, upper winding of relay 960, conductor 921, over the described path, including telephone T^e (key 923 being normal), conductor 928, lower winding of relay 960 to ground. The current derived through the windings of relay 960 will serve as a battery supply for the telephone T^e and will also cause armature 951 to be attracted, extinguishing lamp 952, indicating that the called subscriber at telephone T^e responded and has the receiver thereof off the switchhook. The attendant at the private branch exchange switchboard can restore the listening key 935 at any time after receiving the instructions from the calling subscriber, or the said attendant can listen in on the established telephonic connection between the calling and the called subscriber.

It will now be assumed that the conversation has terminated, and the called subscriber at telephone T^e replaces the receiver first. Under this condition relay 960 will de-actuate and re-establish the current in lamp 952, causing it to glow to indicate to the attendant the condition, so that plug 926 (and in fact plug 902), may be withdrawn, and the service terminated. If plug 902 is withdrawn, from springjack 501 the windings of relay 505 become re-associated in bridge relation between conductors 481 and 419. Bearing in mind that the calling subscriber at telephone T is still holding the receiver, relay 401 and its dependent relay 405 will remain actuated and, therefore, no circuit can be traced to ground from the winding of slow-releasing relay 490, it having remained normal up to this time. Under this condition relay 505 will re-actuate as it will derive current over the traced path including

conductors 481, 519, and the windings of relay 452 which originally energized it as described. This, of course, will cause the calling lamp 508 to re-glow and apprises the attendant at the private branch exchange that the calling subscriber has not replaced his receiver and in all probability desires a further, new connection extended within the private branch exchange. The private branch exchange attendant can re-respond and complete a connection in the manner as before described. However, the private branch exchange attendant would not ordinarily take down the connection completely, in so far as withdrawing plug 902 from springjack 501, until after a clearing signal indicated by the glowing of lamp 917 ensued to indicate that the calling subscriber at telephone T had replaced the receiver, as will be described presently. So, in light of the foregoing, if the attendant withdraws plug 926 from springjack 502 and then does not observe lamp 917 glowing, it will indicate that the calling subscriber at telephone T has not replaced his receiver, and perhaps wants further attention.

It will now be assumed that the calling subscriber at telephone T replaces his receiver. This, regardless of whether the called subscriber at telephone T⁶ has replaced his receiver or that the attendant has withdrawn plug 926 from springjack 502. Upon the calling subscriber replacing his receiver and thereby opening the described energizing circuit of relay 401, dependent relay 405 will de-actuate. It will be borne in mind here that relay 452 will be maintained either through the winding of polarized relay 909, provided the plug 902 is in springjack 501, or through the windings of relay 505, provided said plug 902 has been withdrawn. A circuit can now be traced from grounded armature 440, spring 441, armature 442 to the winding of relay 490, relay 490 actuating. Armatures 491 and 492 will be attracted against their respective make-before-break springs. It will now be seen that the conductive relationship between armatures 479 and 482 and wipers 409 and 410 will be transposed, and that, therefore, the direction of current derived from the windings of relay 452, including conductors 481 and 519, will be reversed and the direction of current traversing the winding of relay 909 (assuming plug 902 to be in spring jack 501) will be such that armature 914 will engage contact 915 and re-establish the glowing of lamp 917. The glowing of lamp 917 will indicate that the calling subscriber at telephone T has replaced his receiver. The attendant will now withdraw the plug 902 from springjack 501.

Bearing in mind that relay 490 is actuated, a circuit path can be traced from the upper winding of relay 452, conductor 485, arma-

ture 478, armature 479, armature 492, wiper 410, bank contact 415, conductor 519, armature 518, spring 517 of springjack 501, lower winding of relay 505 to grounded battery. Grounded battery of the same polarity and voltage is at opposite ends of the path last traced and, therefore, relay 505 is not energized and it remains normal. We may also trace the path from ground through upper winding of relay 505, spring 504, armature 503, conductor 481, contact 414, wiper 409, armature 491, armature 483, conductor 486, lower winding of relay 452, conductor 487, armature 488, conductor 438, to grounded spring 437. There being no energy in the path last traced no electromagnetic effect will be exerted upon relay 505, so that lamp 508 will not re-glow if plug 902 is withdrawn from springjack 501 upon the attendant noting the glowing of lamp 917.

At this instant relay 452 not being energized, an operative circuit can be traced from the winding of release magnet 443, armature 442, spring 441, to grounded armature 440, causing the connector C to be restored to normal. At this juncture, ground potential being removed from bank contact 413 by reason of wiper 408 disengaging, the energizing circuit of relay 492' will be opened and the winding of relay 493 re-applied to armature 494 and to conductor 519, and also ground on contact 495 will be re-applied to armature 496 and to conductor 481 in the well known manner, restoring the first trunk into normal condition in readiness for service originating from either end. It will be assumed now, that the attendant at the private exchange desires to initiate a call on the first trunk of the group and extend it toward a subscriber's line in the main exchange. Plug 902 would be inserted in springjack 501, whereupon a circuit can be traced from grounded battery through winding of relay 493, armature 494, conductor 519, armature 518, spring 517 of springjack 501, ring 913 of plug 902, springs 912 and 910, winding of relay 909, springs 908 and 906, tip 905, spring 504, armature 503, conductor 481, armature 496 to grounded contact 495. The direction of current traversing relay 909 is such as to energize it and hold armature 914 into engagement with contact 915 and, therefore, maintain lamp 917 glowing. Pre-selector PS⁴ will function in the well known manner and seize the first available trunk to a selector (as selector A) of its accessible group, whereupon calling device key 907 may be manipulated and include calling device 960 in series between conductors leading to the tip 905 and the ring 913 of plug 902. Manipulating the calling device 960 will effectuate open impulses constituting digit series effective to control the switches to interlink the first selector with its succeeding connector

to gain connection with the called line, in a manner as has been generally set forth hereinbefore. The calling device key 907 is restored after the digit-train has been sent. 5 Then, upon the called subscriber responding, the connector (B or C) will function to transpose the battery-feed over the calling trunk conductors including the winding of relay 909, thus causing it (909) to disengage 10 its armature 914 from its resting contact 915, whereupon the lamp 917 will extinguish, indicating the condition. Upon the called subscriber replacing his receiver, the current will be caused to traverse the winding 15 of relay 909 in the primary direction, causing lamp 917 to re-glow as a clearing signal. The general functioning of the connectors in effecting the said transposing of the battery-feed is set forth in the Patent 20 No. 13,901, re-issued to Frank Newforth, April 13, 1915.

It will now be assumed that the subscriber at telephone T⁵ desires to call a telephone in the main exchange automatically. Upon 25 removing the receiver from the switchhook the circuit will be established from the winding of relay 525, armature 526, conductor 531, through telephone T⁵, conductor 528' armature 527 to grounded contact 528, causing 30 relay 525 to actuate, whereupon pre-selector PS⁵ will be caused to seize the first available selector I of its accessible group in the manner well known. The selector I has not been detailed in the drawings, though 35 it may be assumed, for example, such a selector as shown in Fig. 8, my pending application serial No. 197,088, filed October 17, 1917. The wipers 540, 541, 542 and 543 are adapted to engage bank contacts 514, 544, 40 545 and 546 respectively located in the tenth level, also referred as the "O" level. Assuming now that the calling subscriber at telephone T⁵ operates the calling device 533 in accordance with the digit "O" and causes 45 the selector I to step its wipers 540, 541, 542 and 543 to align with the "O" level and there rotate-in automatically and seize the first disengaged trunk line, which in this case will be assumed to be the first trunk of 50 the group terminating in bank contacts 514, 544, 545 and 546 respectively. Pre-selector PS⁴ will function as before described when plug 902 was used to initiate an outgoing call, and the call will be continued as before 55 set forth controlled from the calling device 533 in lieu of the calling device 960.

Under the condition of the pre-selector PS⁵ having engaged a selector I, the lower 60 grounded armature 547 of relay 523 will be attracted to close a circuit from grounded battery through lamp 548, causing said lamp to glow, indicating to the attendant that the line leading to telephone T⁵ is in 65 use by reason of a call having been made directly controlled from said T⁵ through

the selector I. It will be noted that the lamp 548 will not glow under any other condition, such as for example, as inserting plug 926 into springjack 502. It is manifest that when selector I seizes as described, 70 bank contact 514 is grounded and, therefore, ground potential will be found on bank contact f, and that ground is communicated through armature 516 to the winding of relay 515, causing it to actuate. Armatures 75 510, 518 and 503 being attracted, springjack 501 is incapacitated, and the trunk concerned cannot be intruded upon therethrough. Grounded armature 549 will apply ground potential to bank contacts e and h. 80

In this connection it will be noted that motor-magnet M will energize and operate as an interrupter, incidentally driving wipers a, b and c one step, into engagement 85 with a successive set of bank contacts. For example, if under the assumed conditions bank contact f constitutes ground potential and wipers a, b and c are at that time resting on bank contacts f, i and h respectively, a circuit would be established from 90 grounded battery through the winding of motor-magnet M, its armature 551, armature 552, conductor 553, wiper a to grounded bank contact f, energizing the motor-magnet 95 M and causing it to operate to advance the wipers a, b and c one step into engagement with bank contacts g, e and d respectively, as shown in the drawings. It will be recalled that the statement was heretofore 100 made that when plug 902 was inserted into springjack 501 or that relay 505 actuated, relay 512 actuated and applied ground from its grounded contact 513 to armature 516 and to the conductor leading to bank contact 514 and multiples thereof. It will thus be manifest that bank contact f will constitute ground potential under all conditions in which the first trunk involving 105 conductors 481 and 519 is busy, regardless of from which end thereof the call is initiated, for, if the call is initiated from the main exchange end, armature 516 serves to apply ground potential to bank contact f, and, if the call is initiated from the private 110 branch exchange end, the wiper 540 of selector I serves to apply ground potential to said bank contact f.

It follows from the foregoing that if the second trunk of the group leading from bank contacts 418 and 419 is busy under any condition, that trunk terminating equipment E will, in a similar manner to that described in relation to the trunk terminating equipment B, apply ground potential to bank contact g, and that trunk terminating equipments F and G will similarly apply ground potential to bank contacts p and t. That is to say, if all four trunks are busy, bank contacts f, g, t 120 and p will constitute ground potential. 125

It has been explained how the motor-magnet M operates to advance the set of wipers *a*, *b* and *c* from a set of bank contacts to the successive set, if the bank contacts engaged by wiper *a* constitutes ground potential. It will be noted from the drawing that wipers *b* and *c* are electrically joined by a tie wire; that armatures 549 and 554 are electrically tied and grounded and that their working contacts are electrically tied and connected to bank contacts *h* and *e*; that armatures 555 and 556 are electrically tied and that their working contacts are electrically tied and connected to bank contacts *d* and *j*; that armatures 557 and 558 are electrically tied and that their working contacts are electrically tied and connected to bank contacts *k* and *m*; that armatures 559 and 560 are electrically tied and their working contacts are tied and also connected to bank contact *n*; that bank contact *i* is permanently grounded, and that armatures 555 and 556 are in common with bank contacts *h* and *e*; that armatures 557 and 558 are in common with bank contacts *d* and *j*; that armatures 559 and 560 are in common with bank contacts *k* and *m*; that when wipers *b* and *c* are in engagement with bank contacts *i* and *h* respectively, it is equivalent to either armature 549 or 554 being attracted; that when wipers *b* and *c* are in engagement with bank contacts *e* and *d* respectively, it is equivalent to either armature 555 or 556 being attracted; that when wipers *b* and *c* are in engagement with bank contacts *j* and *k* respectively, it is equivalent to either armature 557 or 558 being attracted; that when wipers *b* and *c* are in engagement with bank contacts *m* and *n* respectively, it is equivalent to either armature 559 or 560 being attracted.

It has been clearly set forth that the four sets of three bank contacts indicated by *H* correspond in numerical order, as drawn, to the sets of terminating equipments *D*, *E*, *F* and *G*, respectively, and that when the trunk relating to any one of these sets is in a busy state, its bank contact engageable by wiper *a* will constitute ground potential. Further, that wiper *a* cannot rest on a grounded bank contact unless, as will appear, relay 561 is actuated. The relay 561 cannot be caused to actuate unless it derives ground potential through junction point 562. It is manifest that this condition cannot ensue unless all of the armatures 549-554, 555-556, 557-558 and 559-560 are attracted, due to a condition wherein all of the four trunks of the group are busy, or an equivalent condition as relates relay 561, as will appear, is simulated if but three of these four trunks are busy.

As an example, it will be assumed that 65 the first, second and fourth trunks of the

group of four are busy and that, therefore, bank contacts *f*, *g* and *t* constitute ground potential, and that bank contact *p* does not constitute ground potential. It is manifest then that wiper *a* can only find a resting position when it is in engagement with the ungrounded bank contact *p*, under which condition armatures 557 and 558 of terminating equipment set F are normal, because the third trunk corresponding thereto is non-busy. A circuit can now be traced from the winding of relay 561, one of the armatures 559-560 attracted, due to the fourth trunk being busy, conductor 565, bank contact *k*, wiper *c*, through tie wire to wiper *b*, bank contact *j*, conductor 566, one of armatures 555-556 attracted, due to the second trunk being busy, conductor 567, one of armatures 549-554 attracted, due to the first trunk being busy, to ground at junction point 562. Under this condition the energizing circuit to motor-magnet M will be opened at armature 552, so that the wipers *a*, *b* and *c* cannot be driven, regardless of the fact that the third trunk may thereafter become busy and incidentally cause ground potential to be applied to bank contact *p*. Under the condition of relay 561 being actuated, its grounded armature 570 will apply ground potential to conductor 571. This will energize the meter-magnet 572', which is a similar device to that shown in Fig. 1, designated 157, whereupon it will step its indicating drum 573', corresponding to meter drum 161 of Fig. 1, the angular distance corresponding to one unit. The said grounding of conductor 571 completes the energizing circuit of slow-releasing relay 572 by way of armature 573 on relay 574. When relay 572 attracts its armature, a circuit can be traced from grounded armature 575 to the winding of relay 574, and it also applies ground to the free terminal of lamp 576, causing it to glow, and thereby index to the private branch exchange attendant that all of the trunks connecting the main exchange and the private branch exchange, excepting one, are busy. Armature 573 engaging contact 577 following the said actuation of relay 572 will form a locking circuit from grounded conductor 571, armature 573, contact 577 to the winding of relay 574, and this locked condition will continue as long as relay 561 continues energized, which will be until there is more than one non-busy trunk, which, in view of the descriptions, will cause a break in the chained circuit from the winding of relay 561 to ground.

Relay 572 being a slow-releasing relay, its armatures will sustain for its period after armature 573 attracts, and in view of the fact that armature 573 is caused to attract immediately following the actuation of relay 572, the period that relay 572 will

hold its armatures attracted will virtually be equal to the period of its slow-releasing characteristic. From the fact relay 574 is maintained in a locked condition until there 5 are more than one non-busy trunk in the group of four and that lamp 576 will glow as long as the said relay 574 is actuated, the attendant at the private branch exchange, by observing the lamp 576, will know when 10 the critical condition, that of not having more than one available trunk as non-busy, has passed.

The office of relay 572 is very similar to the office of relay 425, the armatures thereof 15 being related at the private branch exchange ends of the trunks to the lower limbs respectively of the four trunks of the group in a similar manner, and further that these armatures respectively co-operate with normally open contacts leading to a special tone source 580 which corresponds to the 20 special tone source 460. Thus, it is manifest that if all but one of the trunks of the group of four becomes busy, the relay 572 25 will apply the special tone 580 to all of the trunks (including the non-busy one) for a brief period, to indicate this fact to all who may be conversing over any of the trunks, the tone becoming audible in the manner as 30 traced and discussed with reference to tone source 460, applied by relay 425. Of course, in the case of relay 425, it only applies tone when all the trunks of the group of four are 35 busy and a call, seeking one of these trunks has been unsuccessful, while in the case of relay 572 applying tone source 580, it applies tone when all but one of the trunks becomes busy, and is not dependent upon a calling subscriber seeking a connection with 40 one of the trunks in the group of four. It is further manifest that due to the distinctive uses and objects of relays 425 and 572, that the special tone sources 460 and 580 45 respectively, controlled by them, may be distinctive so that the character of the tone heard by the auditors conversing on the trunks will indicate to them the specific condition ensuing as set forth.

While the exemplified application of the 50 present invention has related to a specifically described system, it is to be borne in mind, as indicated at the outset, that the described application is but one of many possible applications of it, and furthermore, 55 that the system contemplated in the description would incorporate it in other organizations than have been specifically set forth, but which have been deemed sufficient to clearly disclose its functions and operation.

60 It will also be manifest that while calls have been traced from pre-selectors to first selectors and from first selectors to connectors, that it is entirely feasible and practicable to introduce a second selector intermediate of the first selector and the con-

70 nector, forming what is generally termed a four-digit system, rather than a three-digit system as set forth. Moreover, it will be manifest that a second and succeeding third selector thereto can be, with equal adaptability, introduced intermediate of the first selector and the connector, forming what is generally termed a five-digit system. The 75 said second, and said third selector, would ordinarily be of the same type, and possibly of the same detail, as the first selector. A described, and, in fact, the present invention contemplates the general wiring scheme of the selectors as regards their 80 group arrangement, their leading-in conductors and the bank system accessible to the individual selectors as has been heretofore well known in the art where selectors of the cited classes have been employed, as 85 well as other organizations to which the present invention may be adapted.

90 It will also be manifest that while a group of four trunks has been specifically referred to in the descriptions, the present invention may be applied to smaller or larger groups. 95 Also, that trunks involving the invention may contemplate one-way traffic, rather than two-way traffic, or that some of the trunks may contemplate two-way traffic and others 100 of the same group, one-way traffic.

105 It will also be manifest that the present invention, with particular reference to its features disclosed in Figs. 4 and 5, as relates to the trunks leading from Fig. 4, may be applied between divisions or numerical-order groups of selectors or switches in a system of main-branch offices comprising a comprehensive exchange, or within a main-branch office, as distinct from the described 110 application as applied from a main-branch office to a private branch exchange.

115 It has been set forth hereinbefore how it is necessary to have all four trunks between Figs. 4 and 5 busy, or an equivalent condition set up as relates to relay 561, to cause the relay 572 to actuate and apply the tone source 580. And it has been set forth that the tied wipers *b* and *c* serve to complete the chained circuit operative to relay 561, when any three of the four trunks are busy. 120 It is, therefore, manifest that if the tie conductor connecting wipers *b* and *c* is removed, the condition to cause relay 561 to actuate will only be met by the condition wherein all four trunks are busy, and to change the operative condition wherein the tone from source 580 will be applied only when all the trunks are busy in place of when all but one are busy is a simple one and may be readily changed from time to time to meet the whims of the representatives of the operating concern, or to meet the requirements of the subscriber.

125 Under the condition wherein the tie conductor between wipers *b* and *c* is removed,

the element H has no operative function and object, and it may therefore be disconnected.

The scope of the invention will be comprehended by and in view of the subjoined claims.

I claim:-

1. In a selector adapted to automatically busy-test for the first idle trunk of a group, means to cause its wipers to pass over all trunks of a group being tested regardless of the busy or idle state thereof if control impulses are applied to the selector while it is in the process of said testing.

15 2. In a selector adapted to automatically busy-test for an idle trunk of a group, means to cause its wipers to self-automatically pass over all trunks of a group being tested regardless of the busy or idle state thereof if directive control impulses are applied to the selector's leading-in conductors while it is in the process of said testing.

3. In a telephone system a calling line, a selector, a group of selectors, control means applied to the calling line to directively operate the selector to select the group of selectors, means in the selector for causing it to automatically function to busy-test for and seize an idle selector of the group, and 30 means which will incapacitate the selector against seizing an idle selector if the first said means is operated while the selector is automatically functioning.

4. In a telephone system a calling line, a selector, a group of selectors, means of control on the calling line operative to control the selector whereby the selector will directively select the group of selectors, means in the selector for causing it to automatically function to busy-test for and seize an idle selector of the group, and means which will incapacitate the first said selector against seizing an idle selector of the group if the first said means is operated 45 while the first said selector is automatically functioning.

5. In a selector adapted to be directively operated whereby to select a group of selectors and thereafter automatically function to busy-test for and seize the first idle selector thereof tested, means to cause the selector to function as if all the selectors of the tested group are busy regardless of the busy or idle state thereof if further directive control is applied to the leading-in conductors of the selector before it has seized an idle selector of the group.

6. In a selector adapted to be directively operated to select a group of selectors and thereafter automatically function to busy-test for and seize the first idle selector thereof tested, means to cause the selector to function as if all the selectors of the group tested are busy regardless of the busy or idle state thereof if further directive con-

trol is applied to the selector while it is automatically functioning.

7. In a telephone system a calling line, means of control on the calling line, a selector, a group of selectors, means to cause the selector to operate responsive to the control means to select the group of selectors and thereafter automatically function to busy-test for and seize a trunk leading to the first tested idle selector of the group, and means 70 to incapacitate the selector against seizing a trunk leading to an idle selector of the group if the control means is operated while the selector is in the process of automatic functioning.

8. In a telephone system, a group of lines, a switch normally accessible to the lines of the group respectively, a signal current source, means for operating the switch with relation to the group and thereafter successively busy-testing the lines of the group in automatically hunting for an idle line thereof, and means automatically operative consequent to the switch encountering all the lines of the group as busy to apply the signal current source simultaneously audible along all the lines of the group.

9. In a telephone system, a group of lines, a switch normally accessible to the lines of the group respectively, a signal current source, means for directively operating the switch with relation to the group and thereafter successively busy-testing the lines of the group in automatically hunting for an idle line thereof, and means automatically operative consequent to the switch encountering all the lines of the group as busy to apply the signal current source simultaneously audible along all the lines of the group.

10. In a telephone system, a group of lines, a switch normally accessible to the lines of the group respectively, means for operating the switch with relation to the group and thereafter successively busy-testing the lines of the group in automatically hunting for an idle line thereof, and means automatically operative consequent to the switch encountering all of the lines of the group as busy to apply a signal simultaneously perceptible along all the lines of the group.

11. In a telephone system, a group of lines, means for rendering said lines busy-guarded, and means automatically operative consequent upon all of the lines of the group becoming busy-guarded to simultaneously apply a signal over the lines of the group, the said signal being audible on the said lines to users thereof.

12. In a telephone system, a group of lines, means for rendering said lines busy-guarded, and means automatically operative consequent upon all the lines of the group becoming busy-guarded to simultaneously

- apply an audible signal along the lines of the group for a period and thereafter automatically terminating the signal to the lines, while the said lines remain busy-guarded.
13. In a telephone system, a called line, means for busy-guarding the said line against intrusion, an automatic switch normally accessible to the called line, means for operating the switch into testing relation with the busy-guarded called line, means to restore the said switch, and means automatically operative responsive to the restoration of the switch for applying a signal along the called line.
14. In a telephone system, a calling line, a busy called line, stations on the calling and called lines, an automatic switch terminating an extension of the calling line normally having access to the called line, means at the station on the calling line for directively operating the switch into testing relation with the called line and for normally seizing the called line so a talking relation may be established between the said stations, automatic means for barring the switch from seizing the busy called line, means for restoring the switch after it tests the busy called line, and means operative responsive to restoring the switch for applying a signal discernable at the station on the called line.
15. In a telephone system, a busy called line and station thereon, an automatic switch terminating an extension of the calling line, means for operating the switch into testing relation with the called line, means for guarding the said busy line against intrusion by the switch so the switch will not be enabled to become in talking or signaling connection with the called line, means for restoring the switch after the testing operation, and automatic means effective consequent upon the switch encountering the line guarded whereby a signal will be applied over the called line discernable at the station on the called line incidental to restoring the switch.
16. In a telephone system a calling and a called line connected in talking relation, a second calling line, an automatic switch in access to the connected lines, means in the switch for barring talking relation to the connected lines, and automatic means for applying a tone audible along the connected lines consequent upon selection of one of the connected lines.
17. In a telephone system a calling and a called line in talking relation, a second calling line, an automatic switch in selective access to the connected lines, automatic means in the switch for barring talking relation between the second calling line and the connected lines, and directly controlled means in the switch for applying a tone audible along the connected lines at will.
18. In a telephone system, a calling line leading to a group-selecting switch, a plurality of trunk lines selectively accessible to the switch, a busy-test terminal companion to each trunk line for guarding its companion talking terminals against intrusion, and means including a relay permanently associated with the busy-test terminal of the last accessible said trunk line which will cause an apprising signal to be automatically applied simultaneously audible to users of all the busy said trunk lines consequent upon the said last line being encountered busy.
19. In a telephone system, a calling line leading to a group-selecting switch, a plurality of trunk lines selectively accessible to the switch, a busy-test terminal companion to each trunk line for guarding its companion talking terminals against intrusion, means including a relay permanently associated with the busy-test terminal of the last accessible said trunk line which will cause an apprising signal to be automatically applied simultaneously audible to users of all busy said trunk lines consequent upon the said last line being encountered busy, and automatic means for disconnecting the said signal.
20. In a telephone system, a calling line leading to a group-selecting connecting switch, a plurality of lines selectively accessible to the switch, a busy-test terminal companion to each line accessible to the switch for guarding its companion talking terminals against intrusion, and means including a relay permanently associated with the busy-test terminal of the last said accessible line which will cause an apprising signal to be automatically applied simultaneously audible to users of all the said accessible lines consequent upon the said last line being encountered busy.
21. In a telephone system, a calling line leading to a group-selecting connecting switch, a plurality of lines selectively accessible to the switch, a busy-test terminal companion to each line accessible to the switch for guarding its companion talking terminals against intrusion, and means including a relay permanently associated with the busy-test terminal of the last said accessible line which will cause an apprising signal to be automatically applied simultaneously audible to users of all the said accessible lines consequent upon the said last line being encountered busy, and automatically applied means for disconnecting the said signal.
22. In a telephone system, a calling line leading to a group-selecting switch, a plurality of lines successively accessible from the switch, a busy-test terminal companion to each of said lines for guarding its companion talking terminals against intrusion, and means operative consequent to testing

the last line and finding it busy which will cause a signal to be automatically given observable to the calling line and also otherwise observable independent of the calling line to indicate the condition found.

23. In a telephone system, a calling line leading to an automatic switch, a busy called line normally accessible from the switch, a busy-test terminal companion to the line for guarding the line against seizure due to the busy condition, and means which will cause an apprising signal to be applied to the user of the busy called line consequent upon the said line being encountered busy.

24. In a telephone system, a calling line leading to an automatic switch, a busy called line leading to a station thereon normally accessible from the switch, a busy-test terminal companion to the line for guarding the line against seizure due to the busy condition, and means directly controlled from the calling line for causing an apprising signal to be applied observable at the said station without the called line becoming seized due to the switch having been operated into connective relation with the called line when it is guarded against seizure.

25. In a telephone system, a calling line leading to a switch for automatically hunting over a group of trunks for an idle one thereof to seize, a switch terminating the trunks respectively, control means on the calling line for initiating the said hunting operation of its said switch and for then directly controlling the said terminating switch of the trunk seized, and means in the first said switch operative to disable its containing switch from seizing a tested trunk regardless of its busy or idle state if the said control means on the calling line is operated while the first said switch is in the process of hunting.

26. In a telephone system a first engaged line in a connection between two telephones, a calling line, an automatic switch, means for operating the automatic switch by way of extending the calling line to the first line, means on the calling line for restoring the switch, and automatic means in the switch operative to apply a tone to the first line consequent to the restoration of the switch.

27. In a telephone system, a calling line leading to a switch for automatically hunting over a group of trunks for an idle one thereof to seize, a switch terminating the trunks respectively, control means at a station on the calling line for initiating the said hunting operation of its said switch and for then directly controlling the said terminating switch of the trunk seized, means in the first said switch operative to disable its containing switch from seizing a tested trunk regardless of its busy or idle state if the said control means on the calling line is

operated while the first said switch is in the process of hunting, and means for applying a signal over the calling line to the station thereon to indicate if the control impulses were applied before the trunk was seized. 70

28. In a telephone system, a calling line leading to a switch for automatically hunting over a group of trunks for an idle one thereof to seize, a switch terminating the trunks respectively, control means on the calling line for directly controlling the said terminating switch of the trunk seized, and means in the said first switch operative to disable its containing switch from seizing a tested trunk regardless of its busy or 80 idle state if the said control means on the calling line is operated while the first said switch is in the process of hunting.

29. In a telephone system, a calling line leading to a switch for automatically hunting over a group of trunks for an idle one thereof to seize, a switch terminating the trunks respectively, control means at a station on the calling line for directly controlling the said terminating switch of the trunk seized, means in the said first switch operative to disable its containing switch from seizing a tested trunk regardless of its busy or idle state if the said control means on the calling line is operated while the first said switch is in the process of hunting, and means for applying a signal over the calling line observable at the station to indicate if the control impulses were applied before the trunk was seized. 95

30. In a telephone system, a calling line leading to a switch for automatically hunting over a group of trunks for an idle one thereof to seize, a switch terminating the trunks respectively, control means on the calling line for step directly controlling the first said switch with relation to a group of trunks to be hunted over and also the said terminating switch of the trunk seized, means in the said first switch operative to disable its containing switch from seizing a tested trunk regardless of its busy or idle state if the said control means on the calling line is operated while the first said switch is in the process of hunting, and means involved in the first said means for disabling the said step control of the said switch until the said switch has been restored. 105

31. In a telephone system, a calling line leading to a connecting switch for connection to a called line, a back-bridge relay in the connecting switch, a station on the called line, operating means at the station for actuating the said relay and locking it over a path including a conductor of the called line, means for preventing the said relay being unlocked from the said called station upon restoring the said operating means, and means thereafter controlled from the 110 115 120 125 130

calling line for at will unlocking the said relay.

32. In a telephone system, a calling line leading to a connecting switch for connection to a called line, a release magnet in the connecting switch for restoring the said switch, a back-bridge relay in the said switch for disabling the release magnet, a station on the called line, operating means at the 5 station on the called line for actuating the said relay and for locking it over a path including a conductor of the called line to maintain the release magnet disabled, means for preventing the said relay being unlocked 10 from the calling line, means for preventing the said relay being unlocked from the said called station upon the restoration of the 15 said operating means, and means in control of the calling line after the said restoration 20 of the operating means for at will unlocking the said relay.

33. In a telephone system, a calling line leading to a connecting switch for connection to a called line, a release magnet in the 25 connecting switch for restoring the said switch, a back-bridge relay in the said switch for disabling the release magnet, a station on the called line, operating means at the station on the called line for actuating the 30 said relay and for locking it over a path including a conductor of the called line to maintain the release magnet disabled, means for preventing the said relay being unlocked from the calling line, means for preventing the 35 said relay being unlocked from the said called station upon the restoration of the said operating means, and means in control of the calling line after the said restoration 40 of the operating means, for at will unlocking the said relay and for operating the release magnet to restore the connecting switch.

34. In a telephone system, a calling line leading to a switch in a connection to a 45 called line, a relay in the switch, a station on the called line, operating means at the station for actuating the said relay and locking it over a path including a conductor of the called line, means for preventing the 50 said relay being unlocked from the said called station upon restoring the said operating means, and means thereafter controlled from the calling line for at will unlocking the said relay.

35. In a telephone system, a calling line leading to a switch directly controlled 55 from the calling line for completing a connection to a called line, a relay in the switch, a station on the called line, operating means at the station for actuating the said relay and locking it over a path including a conductor of the called line, means for preventing the 60 said relay being unlocked from the said called station upon restoring the said operating means, and means controlled from the calling line after the said restoration of the operating means for at will unlocking the said relay.

trolled from the calling line for at will unlocking the said relay.

36. In a telephone system, a calling line leading to a connecting switch for connection to a called line, a release magnet in the 70 connecting switch for restoring the said switch, a relay in the said switch for disabling the release magnet, a station on the called line, operating means at the station on the called line for actuating the said relay and for locking it over a path including a conductor of the called line to maintain the release magnet disabled, means for preventing the said relay being unlocked from the calling line, means for preventing the 75 said relay being unlocked from the said called station upon the restoration of the said operating means, and means in control of the calling line after the said restoration of the 80 operating means for at will unlocking the 85 said relay.

37. In a telephone system, a calling line leading to a connecting switch for connection to a called line, a release magnet in the connecting switch for restoring the said 90 switch, a relay in the said switch for disabling the release magnet, a station on the called line, operating means at the station on the called line for actuating the said relay and for locking it over a path including a conductor of the called line to maintain the release magnet disabled, means for preventing the said relay being unlocked from the calling line, means for preventing the 95 said relay being unlocked from the said called station upon the restoration of the said operating means, and means in control of the calling line after the said restoration of the 100 operating means for at will unlocking the said relay and for operating the release magnet to restore the connecting switch.

38. In a telephone system, a calling line leading to a switch directly controlled from the calling line for completing a connection to a called line, a release magnet in the 110 switch for restoring the said switch, a relay in the said switch for disabling the release magnet, a station on the called line, operating means at the station on the called line for actuating the said relay and for locking it over a path including a conductor of the called line to maintain the release magnet disabled, means for preventing the 115 said relay being unlocked from the calling line, means for preventing the said relay being unlocked from the said called station upon the restoration of the said operating means, and means controlled from the calling line after the said restoration of the operating means for at will unlocking the 120 said relay.

39. In a telephone system, a calling line leading to a switch directly controlled from the calling line for completing a connection to a called line, a release magnet in 130

the switch for disabling the release magnet, a station on the called line, operating means at the station on the called line for actuating the said relay and for locking it over a path including a conductor of the called line to maintain the release magnet disabled, means for preventing the said relay being unlocked from the calling line, means for preventing the said relay being unlocked from the said called station upon the restoration of the said operating means, and means controlled from the calling line after the said restoration of the operating means for at will unlocking the said relay and for operating the release magnet to restore the connecting switch.

40. In a telephone system a group of lines each one thereof connected to another line respectively, a calling line, an automatic switch having access to the group, means for operating the automatic switch by way of extending the calling line in the direction of the group, means in the switch for busytesting the lines of the group, and automatically applied means in the switch operative to simultaneously apply a tone to all the lines of the group and their respectively connected lines if all the lines of the group are guarded against seizure.

41. In a telephone system a group of lines each one thereof connected to another line respectively, a calling line, an automatic switch having access to the group, means for operating the automatic switch by way of extending the calling line in the direction of the group, means in the switch for busytesting the lines of the group, and automatically applied means operative to simultaneously apply a tone to all the lines of the group and their respectively connected lines if all the lines of the group are guarded against seizure, when tested.

42. In a telephone system a group of lines, and automatic means for simultaneously applying a tone to all of the lines responsive to all but one of the said lines becoming busy.

43. In a telephone system a group of lines, and automatic means for simultaneously applying a tone to all of the lines responsive to all of the said lines becoming busy.

44. In a telephone system a group of lines, means for connecting the lines thereof to other lines respectively, and means for simultaneously applying a tone to all the lines and their respectively connected lines responsive to all but one of the said lines of the groups becoming busy.

45. In a telephone system a group of lines, means for connecting the lines thereof to other lines respectively, and means for simultaneously applying a tone to all the lines and their respectively connected lines responsive to all of the said lines of the group becoming busy.

46. In a telephone system a group of lines, and means for simultaneously briefly applying a tone to the said lines responsive to a pre-determined number of the said lines becoming busy.

47. In a telephone system a group of lines, and automatic means for simultaneously applying a tone to the said lines responsive to a pre-determined number of said lines becoming busy while a predetermined number of said lines are idle.

48. In a telephone system a group of lines, automatic means for simultaneously applying a tone to the busy lines consequent upon a pre-determined number of lines of the group becoming busy, and a meter device for registering the number of times the said busy conditions ensues.

49. In a telephone system a group of lines, automatic means for simultaneously applying a tone to the lines consequent upon a pre-determined number of lines of the group becoming busy, and a common signal device for indicating the said busy condition.

50. In a telephone system a group of lines, means for simultaneously applying a tone to the lines consequent to all of the lines of the group becoming busy, and a common signal device for indicating the said busy condition.

51. In a telephone system a group of lines, and means for causing a signal device to display consequent upon all of the lines of the group of lines becoming busy to indicate the duration of the said busy condition.

52. In a telephone system a group of lines, and means for causing a signal device common to all the lines to display consequent upon all but one of the group of lines becoming busy.

53. In a telephone system a group of lines, means for connecting the lines thereof to other lines, and means for causing a signal device to display consequent upon all of the lines of the group becoming connected to indicate the duration of the said busy condition.

54. In a telephone system a group of lines, means for connecting the lines thereof to other lines, and means for causing a signal device to display consequent upon a pre-determined number of the lines of the group becoming connected while one of the said lines is not connected.

55. In a telephone system a group of lines, and means for causing a signal device to display consequent upon a pre-determined number of the lines of the group becoming busy while one of said lines is idle.

56. In a telephone system a plurality of trunks, a group of chain relays which will close a chained circuit when all are in an operated state, a switch having circuit-closing wipers and co-operating contact posi-

- tions which are companion to the contacts of the respective relays, a relay of the said chain associated with each of the trunks operated when the trunk is busy, and automatically applied means in the switch for advancing the wipers automatically to an idle contact position whereby when all but one of the trunks are busy the chained circuit will be closed.
57. In a telephone system a plurality of trunks, a group of chain relays which will close a chained circuit when all are in an operated state, a switch having circuit-closing wipers and co-operating contact positions which are companion to the contacts of the respective relays, a relay of the said chain associated with each of the trunks operated when the trunk is busy, and automatically applied means in the switch for advancing the wipers automatically to an idle contact position whereby when all but one of the trunks are busy the chained circuit will be closed and a tone will be applied to the trunks.
58. In a telephone system a plurality of trunks, a group of chain relays which will close a chained circuit when all are in an operated state, a switch having circuit-closing wipers and co-operating contact positions which are companion to the contacts of the respective relays, a relay of the said chain associated with each of the trunks operated when the trunk is busy, and automatically applied means in the switch for advancing the wipers automatically to an idle contact position whereby when all but one of the trunks are busy the chained circuit will be closed and the switch incapacitated against rotating thereafter.
59. In a switch which will automatically rotate its test wiper seeking an idle bank contact upon which to rest consequent to the contact upon which it is then resting becoming busy, automatically applied means for incapacitating the switch from rotating its said wiper when all other contacts normally accessible thereto are busy.
60. In a switch which will automatically rotate its wipers to keep them resting upon a set of bank contacts of a corresponding idle trunk, automatically applied means for incapacitating the switch against rotating the wipers if all but one of the trunks normally accessible through corresponding sets of bank contacts are busy.
61. In a switch which will automatically rotate its wipers to keep them always resting upon a set of bank contacts of a corresponding idle trunk, automatically applied means for incapacitating the switch against rotating the wipers if all of the trunks normally accessible through corresponding sets of bank contacts are busy.
62. In a switch which will automatically rotate its wipers off bank contacts of a busy trunk so as to keep them resting upon the bank contacts of an idle trunk, automatically applied means for incapacitating the switch against rotating the wipers if all but one of the trunks normally accessible to the wipers are busy.
63. In a switch which will automatically rotate its wipers off bank contacts of a busy trunk so as to always keep them resting upon the bank contacts of an idle trunk, automatically applied means for incapacitating the switch against rotating the wipers if all of the trunks normally accessible to the wipers are busy.
64. In a switch which has an advance movement only for its wipers which will automatically rotate its wipers off bank contacts of a busy trunk so as to always keep them resting upon the bank contacts of an idle trunk, automatically applied means for incapacitating the switch against rotating the wipers if all of the trunks normally accessible to the wipers are busy.
65. In a switch which has an advance movement only for its wipers which will automatically rotate its wipers off bank contacts of a busy trunk so as to keep them resting upon the bank contacts of an idle trunk, automatically applied means for incapacitating the switch against rotating the wipers if all of the trunks normally accessible to the wipers, excepting one, are busy.
66. In an automatic telephone system, a hunting switch, a group of trunks, a calling device for directly operating the switch into hunting relation to the group of trunks, and means for disabling the switch from seizing an idle said trunk if the calling device is operated while the switch is hunting.
67. In an automatic telephone system, a hunting switch, a group of trunks, a calling device for directly operating the switch into hunting relation to the group of trunks, and means responsive to the calling device only while the switch is hunting for causing the switch to continue hunting regardless of the busy or idle state of the tested said trunks.
68. In an automatic telephone system, a hunting switch, a group of trunks, a leading-in conductor for the switch, means operated over the leading-in conductor for causing the switch to hunt with respect to the group, and means responsive to control over the said leading-in conductor only during the hunting period for disabling the switch from seizing an idle trunk tested while not disabling the hunting operation of the switch.
69. In a telephone system, a group of lines, a meter device, and automatic means for causing the meter device to integrate the number of times a predetermined number of

- lines of the group become busy while a predetermined number of said lines are idle. 40
70. In a telephone system, a calling line leading to an automatic switch, a busy called line normally accessible from the switch, a busy-test terminal companion to the line for guarding the line against seizure due to the busy condition, means for restoring the operated switch, and means which will cause 10 an apprising signal to be applied to the user of the busy called line consequent upon the said line being encountered busy and the switch thereafter restored. 50
71. In an automatic telephone system, a calling line and station therefor, a called line and station therefor, switch mechanism for connecting the lines operated from the station on the calling line, means dependent upon a manual operation at both said stations 20 for restoring the said mechanism to disconnect the lines, two sources of current for application over the called line, a signal device at the called line station responsive to one said source to indicate when the lines 25 become connected, means for restoring the condition of the signal device and for disconnecting the said one source responsive to a manually applied circuit change at the called line station, and means for applying the 30 other said source to reoperate the signal device responsive to restoring the said manually applied change dependent upon if the calling station has not before effected its restoring operation, to indicate that the calling station has not terminated the call. 35
72. In a switch which will automatically rotate its wipers off busy bank contact sets, a means for disabling the switch from rotating its wipers, and means for operating said
- disabling means responsive to a predetermined number of bank contact sets becoming busy while a predetermined number of said sets are idle. 45
73. In a switch which will automatically rotate its wipers off busy bank contact sets, a means for disabling the switch from rotating its wipers, and means for operating said disabling means responsive to a predetermined number of random said bank contact sets becoming busy while a predetermined 50 number of random sets are idle. 55
74. In a telephone system, a group of lines, a meter device, and automatically applied means for causing the meter device to integrate the number of times a predetermined number of random lines of the group become busy while a predetermined number of random said lines are idle. 60
75. In a telephone system a group of lines, and means for simultaneously briefly applying a tone to the busy said lines responsive to a predetermined number of random said lines becoming busy. 65
76. In a telephone system a group of lines, and means for simultaneously applying a tone to the busy said lines responsive to a predetermined number of said lines becoming busy while a predetermined number of said lines are idle. 70
77. In a telephone system a group of lines, and means for causing a signal device to display consequent upon a predetermined number of random lines of the group becoming busy while a predetermined number of random said lines are idle. 75

In witness whereof, I hereunto subscribe my name this 18th day of May A. D., 1921.

HERBERT M. FRIENDLY.
